UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

Diestock.

1,422,222.

Specification of Letters Patent. Patented July 11, 1922.

Application filed June 25, 1920. Serial No. 391,716.

To all whom it may concern:

Be it known that I, IRA W. NONNEMAN, a citizen of the United States, residing at Warren, in the county of Trumbull and State of Ohio, have invented a certain new and useful Improvement in Diestocks, of which the following is a full, clear, and exact description, reference being had to the accompanying drawings.

10 This invention relates to die stocks and is particularly concerned with that type having a plurality of sets of chasers so mounted that threads of different pitches may be cut on pipes or similar articles of different diameters without removal or replacement of the chasers.

An object of this invention is to provide a simple and effective means for moving one set of chasers, having a given pitch, into an 20 active position, and at the same time to move another set of chasers, having a different pitch, into inactive position. Another object is to provide for positively locking the chasers in any selected position.

25 My invention will be hereinafter more fully described in connection with the drawings and the essential characteristics are set forth in the claims.

In the drawings Fig. 1 is a face or front 30 view of the die stock; Fig. 2 is the same as Fig. 1 with the front plates removed showing the pivoted connection between the chasers; Fig. 3 is an axial section through the die stock; Fig. 4 is a section through the 35 cam plate taken on the line 4—4 in Fig. 5; Fig. 5 is a plan of the cam plate; Fig. 6 is a perspective of one of the chasers; Fig. 7 is a detail showing the connection of a rocking lever with one of the chasers.

40 Designating the parts with the use of reference characters in Fig. 3, 10 represents the frame of the die stock, which has axially aligned inner sleeves 11 and 12. The web 13 extends outwardly from the junction of 45 the inner sleeves, and carries, in addition to the flanges 14 and 15, diametrically opposite sockets 16 and 17, which are internally threaded to receive stock handles 40 and 41.

Slidably mounted within the frame 10 are 50 one set of chasers 18 and another set of chasers 19. These chasers are positioned on the forward end of the frame and may extend through notches in the flanges 12 and 15; the notches having a width substantially 55 equal to the thickness of two of the chasers,

and a depth substantially equal to the width of one of the chasers.

A cam plate 25 rotatably positioned on the sleeve 12 fits against the flange 15. This cam plate is substantially a ring disk having 60 connected arcuate cam grooves cut on the inner face. These grooves as shown in Fig. 5 comprise chaser moving or active grooves 45, for adjustment, and rest grooves 46, connected by transfer grooves 47 which serve 65 to reverse the positions of chasers. The depth of the grooves may be substantially equal to half the thickness of the cam plate, it being only necessary to provide depth sufficient to give good bearing to the pins 70 20 which move therein. A tongue 27 protrudes from the cam plate 25 and serves to provide means by which the operator can rotate the cam plate.

As shown in Fig. 2 a rocking lever 30 75 pivoted on a rock shaft or pin 31 may be bent inwardly at each end and slidably secured at one end to one of the chasers in the set 18, the other end being slidably secured to a chaser of the set 19. The rocking lever may comprise a strip of wire bent to form a loop at its middle portion through which the pin 31 may be inserted, while the outer end may be bent towards the axis of the die stock to permit the ends to engage 85 notches 22 in the chasers.

The pins 31 together with the rocking levers 30 are secured to the frame 10, in the annular portion 23. In this location any movement of the rocking lever will not interfere with any movement of the cam plate 25. To secure the cam plate, after the proper adjustment has been made, by rotating it to the desired position, I may provide a clamping nut 28 which has an internal 90 95 thread adapted to engage a threaded portion of the sleeve 12.

As a convenient means for guiding the die stock when a thread is being cut on a pipe or other article, I provide guide jaws 35 100 slidably mounted in notches with flanges 11 and 14, and provide a cam plate 36 which upon rotation will move the guide bars inwardly or outwardly. I may also provide a lock nut 37 to clamp the cam plate 36 105 when the proper adjustment of the slide jaws 35 has been effected.

In operation, the stock frame is inserted over the end of the pipe or other article to be threaded, the slide jaws adjusted to the 110

outside diameter of the pipe and locked in this position. The chasers having the position desired on the forward end of the die are then moved either inwardly or outwardly by rotation of the cam plate 25. The movement of the chasers is caused by the pins 20 moving in the curved grooves 45 and 46. The pins 20 of the chasers which are in use will occupy the cam grooves 45 and their location in the grooves will be determined by the size of the work being operated on. The chasers which are inoperative will have their pins 20 in the rest groove 46. When a chaser moves from an active to a rest position, the pin moves along the slot and (as best seen in Fig. 5) toward the center of the cam plate until it reaches the outwardly curved portion of the cam whereupon it moves away from the center and towards the rest groove.

The neutral point where the rest and active grooves merge is indicated at 47, and as the pins 20 pass these neutral points the members 30, operated by the pins in the other grooves, will cause the first mentioned pins to properly enter the rest slot 46 so that there can be no jamming action, due to the tendency of the pins to enter the next active groove 45 instead of the rest groove 46. The lever members 30 being made of wire are somewhat resilient or yielding in their action and this causes the pins to enter their proper grooves, even although the latter are worn or somewhat inaccurate. After they have been moved so that they will conform to the size of the pipe to be threaded, then the lock nut 28 is drawn up thus clamping the cam plate against the flange 15 of the frame. During the cutting operation the chasers of the active set are positively locked against outward movement by the walls of the grooves 45, bearing against the pins 20.

To effect an inward or outward movement of the chasers, it is necessary to slacken the nut 28 and to rotate the cam plate 25. The grooves in the cam plate are so designed that an inward movement of the set of chasers 19 effects an outward movement of the chasers in the set 18, as soon as the pins in the chaser enter the transfer grooves 47. The rocking levers which connect the adjacent chasers serve to effect a positive movement of one of the chasers with relation to the adjacent one, and at the same time to prevent any binding action which may occur between the pin and the walls of the groove in the cam plate.

It will thus be seen that I have provided a die stock capable of carrying chasers having different positions and, at the same time that I have provided means for moving one set of chasers relative to the other set. My invention possesses the advantage of positively locking the chasers in any selected position.

65 Further it provides a die stock which is sim-

ple, durable and capable of being cheaply manufactured.

Having thus described my invention, what I claim is:—

1. In a die stock, the combination with a chaser carrying frame, a plurality of sets of radially movable chasers, a cam for simultaneously actuating all sets of chasers, and lever connections extending from a chaser of one set to a chaser of another set. 75

2. In a die stock, the combination with a chaser carrying frame, a plurality of sets of radially movable chasers, means for actuating either set of chasers relative to the other, and lever connections each extending from a chaser of one set to a chaser of another set. 80

3. In a die stock, the combination of a chaser carrier, a cam plate having two sets of cam grooves therein and rotatably mounted on the carrier, a plurality of sets of chasers movable in said carrier, one set of cams being adapted to move one set of chasers into active position, while the other set is moving the other set of chasers into an inactive position, and lever connections between one set of chasers and another. 85 90

4. A cam plate for use in a die stock, comprising a ring disc having connected arcuate grooves therein, said grooves comprising a continuous substantially circular outer rest groove and a set of inner connected arcuate active grooves, said inner grooves having a plurality of points common with the outer groove. 95 100

5. In a die stock, the combination of a chaser carrier, a cam plate rotatably mounted thereon, a plurality of sets of chasers movable in said carrier, said cam plate having active, rest, and intersecting transfer grooves, means connecting the chasers with the said cam whereby movement of the cam effects a relative movement of the said chasers. 105

6. In a die stock, the combination of a chaser carrying frame, two sets of chasers radially movable in said frame and arranged in pairs, comprising a chaser of each set, a cam plate having endless cams adapted to coat with said chasers and to cause relative movement of one set of chasers with another set of chasers, pivoted connections between chasers of one set and those of the other set. 110 115

7. In a die stock, the combination with a chaser carrying frame of a plurality of chasers arranged in sets, a cam plate having grooves therein, a lever pivoted at the center, and connecting at its ends a chaser of one set with a chaser of another set, means on said chaser adapted to engage the grooves in said cam plate, one of said grooves being annular and another of said grooves comprising a series of connected arcuate grooves. 120 125

8. In a die stock, the combination with a chaser carrying frame of a plurality of 130

chasers arranged in sets, a lever pivotally mounted within said frame and connecting a chaser of one set with a chaser of another set, a cam plate having grooves therein comprising active, rest, and transfer grooves, and means on said chasers for engaging the said grooves.

9. In a die stock, the combination with a chaser carrying frame of two sets of chasers arranged in pairs, each pair comprising a chaser of each set, a lever intermediately pivoted and having its ends secured to one chaser of each set, whereby movement of a chaser in one set causes a relative movement 15 of a chaser in another set.

10. In a die stock, the combination with a frame, of a cam plate mounted thereon and having grooves therein, chasers mounted in said frame, projecting members on said 20 chasers for engaging the grooves in said cam plate, said grooves comprising a set of active grooves and a set of rest grooves, one of said sets surrounding the other, and the two sets being connected at spaced points by 25 transfer grooves.

11. In a die stock, the combination with a frame, of a cam plate, having active, rest, and transfer grooves therein and rotatably mounted in the frame, means on the chasers 30 adapted to engage the said grooves, means pivotally mounted on the frame and engaging a pair of adjacent chasers, to shift the chasers from one type of groove to another.

12. In a die stock, the combination with a frame, a plurality of sets of chasers, a cam plate having rest, active and transfer grooves, said rest and active grooves occupying the same circumferential space through a portion of their extent and being 35 connected by said transfer grooves, means on the chasers for engaging the said grooves whereby a relative movement is obtained between the adjacent members of said sets of chasers, and means connecting a chaser of 40 one set with a chaser of another set.

13. In a die stock, the combination with a frame of a cam plate having grooves therein and rotatably mounted in the frame, means on the chasers adapted to engage the said grooves, a lever pivotally mounted on the frame and engaging a pair of adjacent 50 chasers.

14. In a die stock, the combination with a frame, a plurality of sets of chasers, a cam 55 plate having rest and active grooves, said active grooves being spaced radially inwardly of said rest grooves, and transfer

grooves constituting a connection between the other grooves.

15. In a die stock, a chaser carrying frame, 60 sets of chasers arranged together in pairs and adapted to be moved toward and from the work, a cam groove, means adapted to enter the cam groove to move the chasers, and a pivoted lever connecting the adjoining 65 chasers in pairs.

16. In a die stock, the combination of a chaser carrier, a cam plate rotatably mounted thereon, two sets of chasers movable in said carrier, said cam plate having therein 70 a plurality of endless arcuate grooves having common neutral points, projections on said chasers adapted to move in said grooves and means to positively cause the projections in one groove to enter another groove 75 after passing a neutral point.

17. In a die stock, the combination of a chaser holding device, chasers movably arranged in pairs in said device, a cam groove, means coacting with said cam groove, whereby as one chaser of each pair moves towards 80 the work the other moves away, and a yielding lever connecting the adjacent chasers of different sets, whereby during operation said lever will give to prevent any jamming action 85 between the chaser moving means and the cam groove.

18. In a die stock, a chaser carrying frame, two sets of chasers arranged together in pairs and adapted to be moved toward and 90 from the work, a cam groove, means on said chasers adapted to coact with said cam groove to move the chasers toward and from the work, a wire rod connecting the adjacent chasers of different sets and acting to prevent 95 any binding action which might occur between the cam groove and the chaser moving means which coact with the groove.

19. In a die stock, the combination with a frame of two sets of chasers, a cam plate 100 rotatably mounted thereon, said cam plates having sets of active and rest grooves, projecting members on one set of chasers for engaging an active groove and projecting members on the other set of chasers for engaging the rest grooves, and a lever having its ends slidably mounted in a chaser of each set, whereby the chasers of one set are moved to an active groove when the chasers of the other set are moved to the rest groove. 110

In testimony whereof, I hereunto affix my signature.

IRA W. NONNEMAN.
